CLAIM

We claim the ornamental design for a feeder housing for domestic animals, as shown and described.

DESCRIPTION

FIG. 1 is a front perspective view of a feeder housing for domestic animals;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict unclaimed features of the feeder housing for domestic animals that form no part of the design claim but are shown illustratively.
